The Schedule referred to in these Letters Patent, and making part of the same, containing a description of the said device G. Discoll himself of his Improvement in the machine for moulding cracked.

Know all men by these presents that I, John G. Discoll of Auburn in the County of Cayuga and State of New York, have invented and made a new and useful machine or improvement in the making of cracked, & that the following is a full and exact description of the construction of the said machine, & of the method of its operation as invented by me.

The machine is to do the labor of moulding cracked & such other bread as can be moulded with it by flattening the edge of the flat bread after described.

Figure A, on the drawing, is a side view of the effective or working part of the machine, without its frame or any part of its plating. N is shown at twice the size of the other figures. a, is the section of a drum of say about 16 or 18 inches diameter & from one to three feet long, as occasion may require it may be made of wood and turned. This drum a, revolves inside of the part of a cylinder b, which direction is indicated by the arrows. And the dough being cut up in chunks of convenient size is thrown in between the drum and cylinder or at c. By the motion of the drum inside of the cylinder b, rolls the dough, into a long straight roll & the diminution of the space between the cylinder & drum being diminished (as per draft) reduces the roll to a given size & discharges it at d, from whence it rolls down against the spring clapper e, and lies at rest, until the wheel f, turns so far round as to bring the supports g, on each end of this wheel (being as long as a is) in contact with the under edge of the clapper, which is also the same length with the wheel a & h, & raises it up on its springs, high enough for the roll of dough to fall on to the flated surface of the wheel h. & the rotatory motion of this wheel drives it, with a rotatory motion into the space between the wheel f & the clapper, m. (A more particular description of which follows.)

The drum b, may be made of wood & turned smooth & round of any convenient or required length: or if the machine which I have in operation is Fig A, am wish to a foot or four feet in diameter and 16 or 18 inches long. (Two drums are only one foot long) and the wheel h, is made of pine, with a plate of iron cast & put on to the surface of the drum frame, to o. & on the lower sides of the plate is fitted bolts longitudinally, that is from g. to e. & a with plates which are 1/16 of an inch thick & 1/8 in breadth of a convenient thickness, so they may be unnecessary for necessary they are of the above size at the end of it, at a. & 1/4 of a foot from g. & 1/2 of a foot from the wheel h, all the way up to the wheel f, the wheel f, is made of wood & is of great thickness, so that it may hold the plates firmly & not be forced from

within an inch of the end on, to the end of, all the time the machine will do a good business, even if the flats were diminished from end to end. — The cap must be fastened with such relation to the wheel and plates, so that when it is on, one opposite on, the edges between each plate which are about 1/8 of an inch thick, shall come as close together as may be & not create too much friction & the bottoms of the flats should be equidistant from the center of the wheel all the way from end to end & of both fluted plates, that is, the bottoms of the flats of the plate which is on the wheel should be parallel to the surface of the drum itself. & so should those in the cap. The cap is stationary & is the cylinder d. b. —

Now as was mentioned above, when the roller falls into the wheel, b, every turn at the same place, the rotary motion of the wheel gives a like motion to the roll which lies lengthwise of the wheel & because of the flats it rolls down from, g, in the direction of the arrow to m. & as the edges of the flats are constantly approaching each other, until they touch or nearly do at m, the roll of dough is condensed & rolled into balls, and is discharged from the wheel in that shape at m, onto the board, p, from whence they roll on to a table to be finished as the baker may choose. —

The type of the flats may be so varied as to make potato crackers, dada, or butter biscuit, anything of that sort the same or nearly the same effect may be produced with straight plates. — The wheel, b, may be turned in either way as indicated by the arrows in Figs. E. & D. —

The machine may be carried or propelled by a man by the hand, or by a foot-truck like a foot teaming ladder or by any other power, one wheel may carry the other by a step aboard or by a wheel, both without a balance wheel. —

But figs D. & E. on the way of gearing my rear bottom with a crank as at f on B. Sides have a crank attached to the journal of the balance wheel to turn it with the foot as above.

Fig. B. is a view of the front side & fig. C. of the back side. Fig. D. the front and E. the back side of, one to have the fluted wheel go the other way by just inverting or changing ends of the wheel, or of the gearing as in Fig. D. & C. —

It is necessary in some cases to have the flats on the wheel go nearly round it.

All of which I claim as my invention as applied to this above named business, that is I do not claim in relation of cranks, e.g. wheel & hub, whatever is new in this relation, as the whole of fig. A, the application of cranks, wheels &c to this machine as in figs B. & C. D. & E. & the other ways above mentioned.
